MATTRESS FILLING MACHINE

Joseph W. Droll, Chicago, and Alex H. Olson,
Evanston, Ill., assignors to Droll Patents Cor-
poration, Chicago, Ill., a corporation of Dela-
ware

Application January 15, 1936, Serial No. 59,272

40 Claims. (Cl. 226—45)

The invention relates to mattress-filling machines.

The objects of the invention are to provide an improved mattress-filling machine which comprises: a series of longitudinal driven conveyor-members which are spaced apart transversely and form a bed for the filling-material and are adapted to engage and compress the filling-material and deliver it to the spout-section; a series 10 of longitudinal transversely spaced driven conveyors for the filling-material which are transversely adjustable for filling mattresses of different widths; a spout-section for insertion into the mattress-casing, which is composed of longitudinal 15 endless conveyors for delivering the filling into the casing without disarranging the compressed filling; a spout-section which is composed of longitudinal driven conveyors which are transversely adjustable for mattresses of different widths; a compressor-section composed of upper and lower longitudinal driven conveyors which are both inclined relatively to the bed to uniformly compress the filling-material from above and below towards the center of the mass 20 to avoid disarranging the filling-material, particularly when it includes a spring-structure or center; longitudinal driven conveyors which are transversely spaced apart and adjustable, the outermost of which carry the sides for holding the material on the bed, so that when the width of the bed is adjusted the sides will be transversely contracted and expanded with the conveyors and so that when the machine is adjusted for a narrow mattress, the sides and the outermost conveyor 25 30 members will leave the space at the sides of the machine clear for the operator's access to the filling material on the bed; longitudinal units, which are transversely adjustable and include driven conveyors for advancing the mass from the bed, for compressing the material and delivering it into the mattress; conveying elements consisting of chains which engage the filler and which are supported in channel-bars over which the filler travels; improved means for equidistantly spacing and adjusting driven conveyors for filling mattresses of different widths; an improved construction for quickly, evenly and efficiently filling the tick or casing; and other objects which will appear from the detail description.

50 The invention consists in the several novel features which are hereinafter set forth and are more particularly defined by claims at the conclusion hereof.

In the drawings: Fig. 1 is a plan of a machine 55 embodying the invention. Fig. 2 is a longitudinal

section. Fig. 3 is a transverse section through the conveyors of the lower compressor section. Fig. 4 is a detail side elevation of one of the longitudinal units. Fig. 5 is a longitudinal section through the compressor and spout-sections. 5 Fig. 6 is a section on line 6—6 of Fig. 5. Fig. 7 is a detail longitudinal section through a portion of one of the bars of the spout-section. Fig. 8 is a plan of the parts shown in Fig. 7. Fig. 9 is a transverse section on line 9—9 of Fig. 5. 10 Fig. 10 is a transverse section illustrating the screw and mechanism for transverse adjustment of the lower conveyor members. Figs. 11 and 11^a are perspectives of portions of one of the upper compressor-units. Figs. 12 and 12^a are perspectives of one of the lower units. Figs. 13 and 14 are partial side elevations viewed from opposite sides respectively. Fig. 15 is a section on line 15—15 of Fig. 5. Fig. 16 is a view illustrating the connecting members shown in Fig. 15 separated. 20

The invention is exemplified in a machine for filling mattresses which is carried in a framework comprising standards 20, 21, 22, cross-plate 23, cross-bar 24 connecting legs 20, cross-bars 25, 25 26 connecting legs 21, cross-bars 27, 28 connecting legs 22, side-plates 29, 30 connecting legs 21 and 22, and crossed-braces 31 between legs 21 and bar 26, all rigidly secured together to form a supporting structure. 30

The machine comprises a conveyor-section which serves as a bed for receiving the filling-material, a compressor-section with upper and lower convergent conveyors and a spout-section. The receiving-section comprises a transverse 35 series of longitudinal driven conveyor-chains 32. The compressor-section comprises a lower transverse series of longitudinal driven conveyor-chains 33, which receive the filling-material from the conveyors 32, and a corresponding upper 40 transverse series of longitudinal driven conveyor-chains 63. The spout-section comprises a lower series of longitudinal endless conveyor-chains 34 and a corresponding upper series of longitudinal 45 endless conveyor-chains 66, the upper and lower chains being adapted to enter the mattress-casing to deliver the compressed material into it.

A single carrier or support serves as a mounting for each set of longitudinally-aligned chains 32, 33, and 34. These carriers, with the conveyor-chains supported thereby, are spaced apart and adjustable transversely, so they can be spread or brought together for filling mattresses of different widths. Each lower corner consists of a channel-bar 35 for supporting and guiding the 50 55

upper reach of chain 32, a lower channel-bar 36 for guiding the lower reach of chain 32, spacing-blocks 37 between bars 35, 36, an inclined channel-bar 38 for guiding the upper reach of compressor-chain 33, an inclined lower bar 39, plates 40 fixed to bars 35, 36, plates 41 fixed to bars 38, 39, splice-plates 42 between plates 40, 41, a channel-bar 43 for guiding the upper reach of chain 34, and plates 44 between bars 43, 38, and 39, all of which are fixedly secured together. Each chain 32 is driven by a sprocket 46 which is splined to and slidable on a transverse shaft 47 and passes around an idler 48 journaled in a bearing fixed on the under side of bar 35. Each sprocket 46 is confined between plates 40 so it will slide transversely with its carrier. Each lower compressor-chain 33 is driven by a sprocket 49 which is splined to and slidable on a transverse shaft 50 and confined between plates 41 so the chain and sprocket will move transversely with its carrier. The front loop of chain 33 extends around a nose on the front end of bar 38. Each chain 34 is driven by a sprocket 51 which is slidable on and splined to a transverse shaft 52 and is confined between plates 44 of the unit. The front loop of chain 34 passes around a nose-piece 53 on the front end of bar 43. An idler 54 guides the lower reach of chain 34 to retain it in close proximity to the bar 43. Plates 40 and 41 are separably connected by splice-plates 42 to permit the delivery-section to be separated from the compressor and spout-sections in shipment of the machine. Conveyor-chains 32 are omitted from the outermost carriers because they are unnecessary.

The conveyor-chains and upper guide-bars of the lower carriers constitute a bed for retaining the filling-material. Side-plates 45 for retaining the filling-material in the receiving, compressing and spout-sections, are fixedly secured to the outermost bars 35, 38, and 43, so they will be movable transversely with said bars when the carriers and conveyors are adjusted transversely for different widths of mattresses. An attribute of this construction is that when the lower longitudinal conveyors are adjusted transversely for different widths of mattresses, these sides 45 will move inwardly with the bars on the outermost carriers so that there will be no portion of the bed projecting beyond said sides when the bed is contracted for narrow mattresses. This makes it possible for the operator to stand close to the contracted sides and to facilitate the handling of the filling in placing it on the bed and between the sides.

The longitudinally-aligned upper conveyor-chains of the spout and compressor-sections are likewise mounted in unitary carriers for transverse adjustment simultaneously with the lower conveyor-units. Each upper carrier comprises a lower channeled guide-bar 58 for the lower reach of conveyor-chain 63, an upper bar 60, bearing-plates 59, 61, between said bars, and a channel-bar 62 for the upper spout conveyor-chain 66. Each upper compressor-chain 63 is driven by a sprocket 64 which is confined between and journaled in plates 59 and is splined to and slidable on a cross-shaft 71. Each chain 63 extends around an idler 65 which is carried between plates 61. Each upper spout conveyor-chain 66 is driven by a sprocket 67 which is confined between and journaled in plates 61 and is slidable on and splined to a cross-shaft 72. From sprocket 67, chain 66 extends under and along channel-bar 62, thence around a nose-piece 68 on the front end of said

bar and thence under an idler roller 69 journaled in plate 61.

Side-plates 70 are fixedly secured to the carriers for the outermost upper conveyor-units to confine the filling-material to the compressor and spout-sections, so they will be movable transversely with said carriers when the latter are adjusted for different widths of mattresses.

The construction described exemplifies a bed for the filling-material, which is composed of 10 chains and bars which are spaced apart so that the material is carried forward with a minimum of frictional resistance in its passage through the machine. It also exemplifies driven endless delivery, compressor, and spout conveyors which are mounted in, and movable with, transversely adjustable carriers for varying the operative width of the machine. It also exemplifies series of longitudinal driven conveyors for successively delivering filling-material, compressing it, and discharging it into a mattress-casing.

The chains 32 and bars 35 of the receiving-section are horizontal. The lower compressor-chains 33 are inclined upwardly from the point to which the chains 32 deliver the material to the lower spout-chains 34. The upper conveyor-chains 63 are correspondingly inclined downwardly from the points where the top of the mass of material encounters them to the upper spout-chain 66. By thus inclining both the upper and lower compressor-conveyors, the filling-material will be compressed equally from the top and the bottom to preserve the longitudinal arrangement of the filling during its compression, and this is of importance, particularly when a spring-center 35 is used. The upper and lower compressor-chains are driven at a slightly faster rate of travel than the chains 32 and the spout-chains 36 to compensate for their oblique movement relatively to the horizontal line of travel of the material, and so that the mass in transit through the compressor-section will be moved horizontally at the same rate of travel as the mass in the delivery and spout-sections. This also prevents disarrangement of the filling-material during its vertical compression. For this purpose, the sprockets 47 and 64 have slightly larger pitch-diameters than the sprockets which drive the conveyor-chains 32 and the spout conveyor-chains, and the drive-shafts for all of the drive-sprockets are driven at 50 the same speed. The compressor-chains 33 and 63 are preferably provided with lugs 33' and 63' for more effectively gripping the filler-mass as it is advanced and compressed between said chains.

The conveyor-chains are driven from an electric motor 73 by mechanism which comprises a belt 74 driven by the motor; pulley 75 driven by belt 74; shaft 76 which is mounted in journals on frame-plates 30; bevel-gear 78 fixed to one end of shaft 76; bevel-gear 79 meshing with gear 78 and fixed to vertical shaft 80; gear 81 fixed to shaft 80; gear 82 meshing with gear 81 and fixed to shaft 52 which carries the sprockets 51 for driving the spout-conveyor-chains 34; gear 83 65 splined to and slidable on vertical shaft 80; and gear 84 meshing with gear 83 and splined to cross-shaft 72 for driving the sprockets 67 for the upper conveyor-chains 66.

Shaft 50, which carries the sprockets 47 for driving the lower compressor-chains 33, is driven from the shaft 52 by a sprocket 85 fixed to one end of shaft 52, a sprocket-chain 86 driven by sprocket 85, and a sprocket 87 driven by said chain and fixed to one end of the shaft 50. Shaft 47, which 75

carries sprockets 46 for driving chains 32 of the delivery-section, is driven from shaft 50 by a sprocket 89 fixed to the latter shaft, a sprocket-chain 90 and a sprocket 91 fixed to one end of shaft 47. Shaft 71, which carries sprockets 64, which drive the upper compressor-chains 63, is driven by a sprocket 92, which is fixed to one end of shaft 72, a sprocket-chain 93 driven by sprocket 92 and a sprocket-wheel 94 fixed to one end of shaft 71.

Shafts 52, 72, 47, 50, and 71 which drive the conveyors, are driven at the same speed. The sprockets 67 and 51 for the spout-conveyors and the sprockets 46 for the delivery conveyors are of the same size so that the conveyor-chains 32, 34, and 66 will advance the filling material at a uniform rate of travel and sprockets 64 and 49, which drive the inclined compressor-conveyor-chains, are slightly larger in pitch-diameter than the sprockets for the delivery and spout-conveyors to cause the compressor-conveyors to be driven slightly faster but to advance the mass longitudinally at the same rate of travel while simultaneously compressing it vertically. This insures the vertical compression of the filler-mass and its advance through the machine at a uniform rate of travel which prevents the disarrangement of the filling and is of special importance when the filling comprises a series of springs, which would become deflected or disarranged if the material at the top moved differentially with respect to the material at the bottom.

The carriers for the lower chains 32, 33, and 34, with their drive-sprockets, are separately slideable on the drive-shafts 47, 50, and 52 transversely of the bed, so that transverse variation of the spacing between the carriers will correspondingly adjust the conveyor-chains and their drive-sprockets. The carriers for the upper compressor and spout conveyor-chains, with their drive-sprockets, are slideable on the shafts 71, 72 and chains 63 and 62, with their drive-sprockets, are movable with the carriers, respectively. All of the drive sprockets for the several conveyor chains are splined to, and slideable on, their respective drive-shafts to maintain the driving relation between the shafts and the conveyor-chains in their different transverse adjustments.

Mechanism for equidistantly and simultaneously adjusting the carriers for the upper and lower conveyor-chains, with their drive-sprockets, transversely to narrow the conveyor-structure of the machine, including the sides, for narrow mattresses and spreading it for wide mattresses, comprises a screw-shaft 97 extending transversely through plates 44 of the entire series of lower carriers and a screw-shaft 98 extending through the plates 61 of the entire series of upper carriers, and gearing for conjointly rotating screw-shafts 97, 98. Shaft 97 is adapted to be rotated manually, being provided with a polygonal end, so that a crank can be attached thereto. When screw-shaft 97 is rotated, shaft 98 will be correspondingly rotated by a gear 99 fixed to shaft 97, a gear 100 meshing with gear 99 and fixed to a vertical shaft 101, a gear 103 splined to shaft 101 and a gear 104 fixed to screw-shaft 98 and meshing with gear 103. Screw-shafts 97, 98 are each provided with right and left-hand threads, which engage nuts 105 which are fixed to the outermost carriers of the upper and lower series, respectively. These shafts extend loosely through all of the intermediate carriers so that rotation of the screw-shafts 97, 98 in one direction will shift the outermost carriers together and reverse rotation

will spread them. The two centrally disposed carriers of the upper and the lower series are fixedly held against transverse movement by means, such as collars 106 fixed to the drive-shafts 52, 72, respectively. The groups of carriers between the central fixed carriers and the outermost carriers of the upper and lower series, which are shiftable through nuts 105 by shafts 97, 98, are each shifted for uniform spacing by a system of crossed levers. Each of these systems 10 comprises a series of parallel levers 109 and a series of parallel levers 110 which cross, and are pivoted at their crossings to, levers 109. The end levers 110 of each system are pivoted to an outermost carrier and the end levers 109 of the same 15 system are pivoted to one of the central fixed carriers. A pair of intermediate levers, one from each series, is pivoted to each of the intermediate carriers, so that transverse movement of each outermost carrier will shift one entire system of 20 crossed levers to equidistantly shift and space the intermediate carriers and conveyors mounted therein. Like systems of crossed levers are applied to the upper and lower carriers. This exemplifies means for equidistantly spacing the 25 carriers and conveyor-chains at both sides of the longitudinal center of the machine when the transverse adjusting mechanism is operated to rotate the screw-shafts 97, 98.

Mechanism is provided for keeping the carriers 30 and the conveyor-chains parallel in the transverse adjustment thereof and while they are set for mattresses of different widths. For this purpose, each lower carrier has a journal for a shaft 114, which underlies the carrier. A pinion 115 35 is fixed to each shaft 114. All of these pinions mesh with a transverse rack 107 which has its ends fixed to the supporting frame of the machine. Each shaft 114 is connected by a universal joint 118 to a shaft 116 which underlies the carrier and 40 is journaled in bearings 117 mounted on the carrier. Each shaft 116 has fixed thereto a pinion 119, which meshes with a transverse rack 120 which extends across the machine and has its ends fixed to the supporting frame of the machine. 45 A pinion 122 is fixed to the rear end of shaft 116. These pinions 122 mesh with a transverse rack 123 which extends across, and is fixed to, the transverse angle-bar 24 of the supporting-frame.

A shaft 125 overlies, and is journaled in bearings 50 on the top of, each of the upper carriers. Each shaft 125 has affixed thereto a pinion 126 which meshes with a transverse rack 127 and a pinion 128 which meshes with a rack 129. Racks 127 and 129 have their ends fixed to the supporting-frame for the upper carriers and conveyors.

When the upper and lower carriers are adjusted transversely, as the result of rotation of screw-shafts 97, 98 and the crossed systems of levers, 60 pinions 115 will be shifted bodily and rotated by the fixed rack 107 to rotate shafts 114, 116 which will impart rotation to pinions 119, 122 to cause all of the lower carriers to move rectilinearly. Simultaneously, the transverse movement of the 65 upper carriers will bodily shift pinions 126, which mesh with fixed rack 127, so they will rotate pinions 128, which mesh with fixed rack 129, so that the upper carriers and the conveyors mounted therein, will be adjusted rectilinearly. 70

The carriers for the upper compressor and spout-conveyors are vertically adjustable for spacing them from the lower carriers and conveyors for producing mattresses of different thicknesses. Drive-shafts 71, 72 and screw-shaft 75

98 are carried in journals fixed to vertically adjustable plates 102 and transverse racks 127, 128 are also fixed to said plates. These plates are fixed to standards 131 which are vertically slidable in the standards 21, 22 of the stationary framework which supports the lower carriers so that all of the upper carriers and conveyors carried by plates 102 may be unitarily raised or lowered. Mechanism for effecting this vertical adjustment comprises a transverse shaft 135, which is rotatable by a crank and is journaled in the stationary framework and provided with a pair of worms 136; worm-gears 137 meshing with worms 136, respectively, longitudinal shafts 138, to which gears 137 are fixed; and pinions 139 fixed to shafts 138 and meshing with rack-teeth 140 on the standards 131. When the operator rotates shaft 135, plates 102 and all of the parts carried thereby, which include the upper compressor and spout-chains, the carriers therefor, and the mechanism for transversely adjusting said carriers, will be raised or lowered as desired. Gear 93, which drives the sprocket-shaft 12 through which the upper conveyor-chains are driven, is slidable on the vertical shaft 80 with standards 131 to maintain the driving connection for the upper conveyors in all vertical settings. Gear 103 which operates the upper screw-shaft 98 for transversely adjusting the upper carriers, is also slidable vertically with plates 102 to maintain operative relation between shaft 100 and said screw-shaft 98. This exemplifies mechanism for vertically shifting the upper compressor and spout-conveyors and the carriers therefor for producing mattresses of different thicknesses.

The chains for all of the endless chain-conveyors are preferably of the roller-type and comprise link-sides 140, cross-pins 141, and rollers 142. The edges of the links are curved inwardly between their round end-portions so the link will enter, engage and definitely advance the mass of material and so as to avoid slippage. The longitudinal channel-bars which guide the reaches of the chains which engage the filling, such as bars 35, 38, 42, 62, and 58 are each provided with a raised track 143 which is engaged by the rollers to hold the active reaches of the chains in their paths with a minimum of frictional resistance. The peripheries of the rollers are inwardly of the edges of the links so the latter will project into the material. The side flanges on said bars, where they guide the material-engaging portions of the chains, are reduced in height so the chains will project from the bars and into the filling to effectively engage it.

The operation of the machine is as follows: The operator will place the material for filling a mattress in the receiving-section so that it will be retained on the conveyor-chains 32 and the bars 35 between the sides 45. A mattress-casing *a* will be placed over the spout-section to receive the material. When the entire material for filling a mattress has been thus placed, the motor 73 is operated to drive the endless conveyor-chains 32, upper and lower compressor-chains 33 and 63, and the spout-chains 34, 66. The conveyor-chains 32 will feed the material forwardly to the convergent endless compressor-chains 33, 63, between which the material will be compressed from above and below, and fed forwardly at the same rate of travel as the material being advanced by the chain-conveyors 32. During this compression, the material will be compressed from above and below so that its vertical center will correspond substantially with

the vertical center of the uncompressed material and so as to prevent disarrangement of the material and the springs therein. The compressor-chains deliver the compressed mass to the lower reach of the upper, and the upper reach of the lower, spout chain-conveyors, which will advance the compressed material into the casing and force the filled portion of the casing away from the spout until the casing has been completely filled. In this operation the material is definitely, continuously, and uniformly advanced by the chain-conveyors which are spaced apart transversely. The compressed material will be definitely advanced by the spout-conveyors with a uniform density, so the material will be uniformly delivered into the casing. When it is desired to change the operative width of the machine for mattresses of different width, it is only necessary for the operator to rotate shaft 97 by means of a crank applied thereto, which will vary the transverse spacing between the carriers and conveyor-chains equidistantly and simultaneously. The sides 45 and 70 which retain the material on the conveyors will be adjusted transversely simultaneously with the carriers so that the operator can stand close to the sides of the machine and conveniently place the filling-material in the receiving-section of the machine. When the operator desires to set the machine for a mattress of different thickness, it is only necessary to rotate shaft 135 by means of a crank to raise or lower the upper conveyors and carriers as desired.

The invention is not to be understood as restricted to the details set forth, since these may be modified within the scope of the appended claims, without departing from the spirit and scope of the invention.

Having thus described the invention, what we claim as new and desire to secure by Letters Patent is:

1. In a machine for filling mattresses, the combination of a supporting frame, means for holding a mattress-casing in position to be filled with a mass of material, means for compressing and delivering the compressed filling material into the casing comprising a series of longitudinally movable conveyors for engaging and advancing the mass of filling material, the conveyors having transverse open spaces between them and being sufficient in number to retain and convey the mass along and over the open spaces, and means for driving the conveyors to deliver the material into the mattress-casing.

2. In a machine for filling mattresses, the combination of a supporting frame, means for holding a mattress-casing in position to be filled with a mass of material, means for compressing and delivering the compressed filling material into the casing, comprising a series of longitudinally movable endless conveyors for engaging and advancing the mass of filling material, the conveyors having transverse open spaces between them and being sufficient in number to retain and convey the mass over and along the open spaces, and means for driving the conveyors to deliver the material into the casing.

3. In a machine for filling mattresses, the combination of a supporting frame, means for holding a mattress-casing in position to be filled with a mass of material, means for compressing and delivering the compressed filling material into the casing comprising a series of longitudinal carriers, a series of endless chains mounted on, and confined in, said carriers, re-

spectively, for engaging and advancing the mass of filling material, the carriers having transverse open spaces between them, and being sufficient in number to retain and convey the material over 5 and along the open spaces, and means for driving the chains to deliver the material into the casing.

4. A machine of the character described, comprising the combination of a supporting frame, 10 a series of longitudinally movable conveyors for engaging and advancing a mass of filling material, said conveyors having transverse open spaces between them, being sufficient in number to retain and convey the mass of material at the 15 open spaces between the conveyors and being transversely adjustable in the frame to vary the spacing between them for filling casings of different widths, means for driving the conveyors, and means for delivering the material into 20 a casing.

5. A machine of the character described, comprising the combination of a supporting frame, a series of longitudinally movable endless conveyors for engaging and advancing a mass of filling 25 material, said conveyors having transverse open spaces between them, being sufficient in number to retain and convey the mass of material at the open spaces between the conveyors and being transversely adjustable in the frame to vary the 30 spacing between them for filling casings of different widths, means for driving the conveyors, and means for delivering the material into a casing.

6. A machine of the character described, comprising the combination of a supporting frame, 35 a series of longitudinal carriers, longitudinal conveyor-chains mounted on said carriers, respectively, for engaging and advancing a mass of filling material, said conveyors and carriers having 40 transverse open spaces between them, being sufficient in number to retain and convey the mass of material at the open spaces between the conveyors and being transversely adjustable in the frame to vary their spacing for filling casings 45 of different widths, means for driving the conveyors, and means for delivering the material into a casing.

7. A machine of the character described, comprising the combination of a supporting frame, 50 a series of longitudinally movable conveyors for engaging and advancing a mass of filling material, said conveyors having transverse open spaces between them and being sufficient in number to retain and convey the mass of material at the 55 open spaces between the conveyors, mechanism for driving the conveyors to advance the filling, means for simultaneously and equidistantly adjusting the conveyors transversely to vary their spacing for casings of different widths, and means 60 for delivering the filling material into the casing.

8. A machine of the character described, comprising the combination of a supporting frame, a series of longitudinal endless conveyors for engaging 65 and advancing a mass of filling material, said conveyors having transverse open spaces between them and being sufficient in number to retain and convey the mass of material at the open spaces between the conveyors, mechanism 70 for driving the conveyors to advance the filling, means for simultaneously and equidistantly adjusting the conveyors transversely to uniformly vary their spacing for casings of different widths, and means for delivering the filling material into 75 a casing.

9. A machine of the character described, comprising the combination of a supporting frame, longitudinal carriers supported by the frame, longitudinally movable conveyors individually mounted on the carriers for engaging and advancing filling material, the carriers and conveyors having transverse open spaces between them and being sufficient in number to retain and convey the mass of material at the open spaces between the conveyors, means for transversely and conjointly adjusting the carriers and conveyors to vary their spacing for casings of different widths, mechanism for driving the conveyors to advance the material, and means for delivering the material into a casing. 10

10. A machine of the character described, comprising the combination of a supporting frame, a series of longitudinal carriers supported by the frame, longitudinally movable endless conveyors separately mounted on the carriers for advancing a mass of filling material, the carriers having transverse open spaces between them, the carriers and conveyors being sufficient in number to retain and convey the mass of material at the open spaces between the conveyors, means for 25 transversely adjusting the carriers and conveyors to vary their spacing for casings of different widths, mechanism for driving the conveyors to advance the material, and means for delivering the material into a casing. 30

11. A machine of the character described, comprising the combination of a series of lower longitudinally movable conveyors for engaging and advancing filling material, upper and lower series of longitudinally movable conveyors for compressing material, the conveyors of all of said series having transverse open spaces between them and being sufficient in number to retain and convey the mass of material at the open spaces, means adapted to extend into and deliver the material 35 into a casing, individual longitudinally extending supports for the conveyors respectively with corresponding spaces between them and means for driving all of the conveyors. 40

12. A machine of the character described, comprising the combination of a series of longitudinal endless conveyors for engaging and advancing filling material, upper and lower series of longitudinal endless conveyors for compressing material, the series of advancing conveyors and the upper and lower compressor conveyors having 50 transverse open spaces between them and being sufficient in number to retain and convey the mass of material at the open spaces, means adapted to extend into and deliver the material into 55 a casing, individual longitudinally extending supports for the conveyors respectively with corresponding spaces between them and means for driving all of the conveyors. 60

13. A machine of the character described, comprising the combination of a series of longitudinally movable lower conveyors for engaging and advancing filling material, upper and lower series of longitudinally movable conveyors for compressing the material, longitudinally movable conveyors adapted to extend into and deliver the material into a casing, all of the conveyors having transverse open spaces between them and being sufficient in number to retain and convey the mass of material at the open spaces individual 65 longitudinally extending supports for the conveyors respectively with corresponding spaces between them and means for driving all of the conveyors. 70

14. A machine of the character described, com- 75

prising the combination of a series of longitudinal endless conveyors for engaging and advancing filling material, upper and lower series of longitudinal endless conveyors for compressing material, longitudinal endless conveyors adapted to extend into and deliver the material into a casing, all of the conveyors having transverse spaces between them and being sufficient in number to retain and convey the mass of material at the open spaces between the conveyors, individual longitudinally extending supports for the conveyors respectively with corresponding spaces between them and means for driving all of the conveyors.

15. A machine of the character described, comprising the combination of a series of transversely-spaced longitudinally movable lower conveyors for engaging and advancing filling material, upper and lower series of transversely-spaced longitudinally movable conveyors for compressing the material, transversely spaced longitudinally movable conveyors adapted to extend into and deliver the material into a casing, means for conjointly adjusting the several series of conveyors to vary their spacing for casings of different width, and means for driving all of the conveyors.

16. A machine of the character described, comprising the combination of a series of transversely-spaced longitudinal endless conveyors for engaging and advancing filling material, upper and lower series of transversely-spaced longitudinal endless conveyors for compressing the material, transversely spaced longitudinal endless conveyors adapted to extend into and deliver the material into a casing, means for conjointly adjusting the several series of conveyors to vary their spacing for casings of different width, and means for driving all of the conveyors.

17. A machine of the character described, comprising the combination of a supporting-frame, a series of longitudinally-operated receiving-conveyors, a series of longitudinally-operating compressor-conveyors, a series of spout-conveyors, a series of separate carriers in which the longitudinally-aligned conveyors of the three series are mounted, mechanism for adjusting the carriers transversely for casings of different widths, and mechanism for driving the conveyors.

18. A machine of the character described, comprising the combination of a supporting-frame, a series of longitudinally-operated receiving-conveyors, series of upper and lower longitudinally-operating compressor-conveyors, series of upper and lower spout-conveyors, a series of separate carriers in which the longitudinally-aligned conveyors of the receiving and lower compressor and spout conveyors are mounted, a series of separate carriers in which the conveyors of the upper compressor and spout-conveyors are mounted, mechanism for simultaneously adjusting the carriers transversely for casings of different widths, and mechanism for driving the conveyors.

19. In a machine of the character described, the combination of a supporting-frame, a conveyor-section supported by the frame, for receiving the filling material, coacting upper and lower conveyors for compressing the material, the lower being inclined upwardly from the receiving-section, the upper being correspondingly inclined downwardly from the receiving-section, a spout-section into which the compressed material is delivered, and means for driving the compressor-conveyors.

20. In a machine of the character described, the combination of a supporting-frame, a con-

veyor-section supported by the frame for receiving the filling material, series of transversely-spaced coacting endless upper and lower conveyors for compressing the material, the lower being inclined upwardly from the receiving-section, the upper being correspondingly inclined downwardly from the receiving-section, a spout-section into which the compressed material is delivered, and means for driving the compressor-conveyors.

21. A machine of the character described, comprising the combination of a supporting-frame, means for receiving filling-material and advancing it longitudinally, compressing-means to which the material is delivered, series of longitudinal driven upper and lower conveyors forming a spout and adapted to extend and deliver the material into a mattress-casing, the conveyors forming the spout having transverse open spaces between them and being sufficient in number to retain and convey the mass of material at the open spaces, and mechanism for driving said conveyors.

22. A machine of the character described, comprising the combination of a supporting-frame, means for receiving filling-material and advancing it longitudinally, compressing-means to which the material is delivered, series of longitudinal driven upper and lower endless conveyors forming a spout and adapted to extend and deliver the material into a mattress-casing, the conveyors forming the spout having transverse open spaces between them and being sufficient in number to retain and convey the mass of material at the open spaces, and mechanism for driving said conveyors.

23. A machine of the character described, comprising the combination of a supporting-frame, means for receiving filling-material and advancing it longitudinally, compressing-means to which the material is delivered, a series of upper and a series of lower longitudinal conveyors forming a spout and adapted to extend and deliver the material into a mattress-casing, said conveyors having transverse open spaces between them and being sufficient in number to retain and convey the mass of material at the open spaces between the conveyors and mechanism for driving said conveyors.

24. A machine of the character described, comprising the combination of a supporting-frame, means for receiving filling-material and advancing it longitudinally, compressing-means to which the material is delivered, longitudinal driven upper and lower conveyors forming a spout and adapted to extend and deliver the material into a mattress-casing, the conveyors having transverse open spaces between them and being sufficient in number to retain and convey the mass of material at the open spaces between the conveyors, means for vertically adjusting the upper conveyors for filling mattresses of different thickness, and mechanism for driving said conveyors.

25. A machine of the character described, comprising the combination of a supporting-frame, a section for receiving the filling material, coacting upper and lower chain-conveyors for compressing and advancing the material, the lower of which is inclined upwardly from the receiving-section, and the upper of which is correspondingly inclined downwardly from the receiving-section, means for driving the compressing-conveyors and a spout to which the compressor-conveyors deliver material.

26. A machine of the character described, com-

prising the combination of a supporting-frame, a section for receiving the filling material, series of coacting upper and lower longitudinal transversely-spaced endless conveyors for compressing and advancing the material, the lower series being inclined upwardly from the receiving-section, the upper series being correspondingly inclined downwardly from the receiving-section, and means for driving the compressing-conveyors and a spout 5 to which the compressor-conveyors deliver material.

27. A machine of the character described, comprising the combination of a supporting-frame, a bed for a mass of filling-material comprising 15 transversely-spaced and transversely-adjustable longitudinally movable conveyor-members, transversely-movable sides for holding the material on the bed, means for conjointly adjusting the sides and the members for filling casings of different widths, and means for delivering the material into a casing.

28. A machine of the character described comprising the combination of a supporting-frame, a bed for a mass of filling-material comprising 25 transversely-spaced and transversely-adjustable lower and upper longitudinally movable conveyors, transversely-movable sides for holding the material on the bed, means for conjointly adjusting the sides and the conveyors for filling 30 casings of different widths, and means for delivering the material into a casing.

29. A machine of the character described comprising the combination of a supporting-frame, a bed for a mass of filling material comprising 35 upper and lower series of transversely-spaced and transversely-adjustable bars and longitudinal conveyor-members carried by the bars, upper and lower transversely-movable sides for holding the material, and attached to the outermost bars, 40 means for conjointly adjusting the sides and the bars for filling casings of different widths, and means for delivering the material into a casing.

30. In a machine for filling mattresses, the combination of a supporting frame, means for holding 45 a mattress-casing in position to receive a compressed mass of filling material, means for compressing and filling the casing with the material comprising longitudinally movable endless conveyor chains for engaging and advancing the filling material, longitudinal bars for guiding the chains, respectively, the chains and bars having open and transverse spaces between them and being sufficient in number to retain the mass of material at the open spaces, drive sprockets at one end of 50 the conveyor chains, narrow fixed members on the opposite ends of the bars for guiding the opposite looped ends of the conveyors, and means for driving the sprockets to advance the material into the casing.

31. In a machine for filling mattresses, the combination of a supporting frame, means for holding a mattress-casing in position to receive the filling material, means for compressing and filling the casing with the material comprising 55 transversely spaced longitudinally movable endless conveyor chains for engaging and advancing the filling material, transversely spaced longitudinal bars for guiding the chains, respectively, the conveyor chains comprising rollers and links, 60 the bars having tracks engaged by the rollers, and flanges at the outer sides of the links, and mechanism for conjointly driving the chains to advance the material.

32. In a machine for filling mattresses, the combination of a supporting frame, means for 65

holding a mattress-casing in position to receive the filling material, means for compressing and filling the casing with the material comprising transversely spaced longitudinally movable endless conveyor chains for engaging and advancing the filling material, transversely spaced longitudinal bars for guiding the chains, respectively, the conveyor chains comprising rollers and links, the bars having tracks engaged by the rollers and channels in which the chain-links are 10 held transversely, and mechanism for conjointly driving the chains to advance the material into the casing.

33. In a mattress-filling machine, the combination of a supporting-frame, lower transversely- 15 adjustable, longitudinally - movable conveyors supported by the frame, upper transversely-adjustable, longitudinally-movable conveyors, supporting-means for the upper conveyors supported for vertical movement by the frame, mechanism 20 for raising and lowering the upper conveyors, upper and lower endless conveyors forming a spout for delivering material into a casing, the lower spout-conveyors being supported by the frame, the upper spout-conveyors being movable 25 with the vertical supporting-means for the first mentioned upper conveyors, mechanism for driving the conveyors, and mechanism for raising and lowering said supporting-means.

34. A mattress-filling machine comprising the 30 combination of a supporting-frame, a section for receiving the filling comprising a longitudinally-movable conveyor, coacting upper and lower conveyors for compressing and advancing the material from the receiving-section, the lower of which 35 is inclined upwardly from the receiving-section, and the upper of which is inclined downwardly from the receiving-section, a spout to which the compressor-conveyors deliver the material, mechanism for driving the receiving-conveyor, and 40 mechanism for driving the compressing-conveyors at a higher rate of travel than the receiving-conveyor to cause the material to move horizontally at a uniform rate of travel in the receiving-section and between the compressing-conveyors. 45

35. In a mattress-filling machine, the combination of a supporting frame, means for longitudinally advancing and compressing a mass of filling-material, upper and lower series of longitudinal endless substantially parallel conveyors 50 forming a spout adapted to extend and deliver the material into a mattress-casing, having transverse open spaces between them, sufficient in number to support the mass of material between the conveyors, and transversely adjustable to vary 55 the spacing between them for filling casings of different widths, and mechanism for driving said conveyors.

36. In a mattress-filling machine, the combination of a supporting frame, means for longitudinally advancing and compressing a mass of filling-material, upper and lower series of longitudinal endless substantially parallel conveyors forming a spout adapted to extend and deliver the material into a mattress-casing, having transverse open spaces between them, sufficient in number to support the mass of material between the conveyors, and transversely adjustable to vary 65 the spacing between them for filling casings of different widths, mechanism for equidistantly and 70 conjointly adjusting the conveyors transversely, and mechanism for driving said conveyors.

37. In a mattress-filling machine, the combination of a supporting frame, means for longitudinally advancing and compressing a mass of 75

filling-material, upper and lower series of longitudinal endless substantially parallel conveyors forming a spout, adapted to extend and deliver the material into a mattress-casing, having transverse open spaces between them, sufficient in number to support the mass of material between them, individual longitudinal guides for the spout conveyors, and mechanism for driving said conveyors.

38. In a mattress-filling machine, the combination of a supporting frame, means for longitudinally advancing and compressing a mass of filling-material, upper and lower series of longitudinal endless substantially parallel conveyors forming a spout adapted to deliver the material into the casing, having transverse open spaces between them sufficient in number to support the mass of material between the conveyors, and transversely adjustable in the frame to vary the spacing between them for filling casings of different widths, individual longitudinal guides for, and adjustable with, the spout-conveyors, and mechanism for driving said conveyors.

39. In a mattress-filling machine, the combination of a supporting frame, means for longitudinally advancing and compressing a mass of

filling-material, upper and lower series of longitudinal endless substantially parallel chains forming a spout adapted to deliver the material into the casing, having transverse open spaces between them, sufficient in number to support the mass of material between the conveyors, individual supporting bars having channels for the conveyors, fixed narrow guides on the outer ends of the bars around which the chains are looped, and mechanism for driving said chains.

40. In a mattress-filling machine, the combination of a supporting frame, means for longitudinally advancing and compressing a mass of filling-material, upper and lower series of longitudinal endless substantially parallel chains forming a spout adapted to deliver the material into the casing, having transverse open spaces between them, sufficient in number to support the mass of material between the conveyors, individual supporting bars having channels in the top and bottom thereof in which the oppositely moving reaches of the chains are guided, respectively, and mechanism for driving the chains.
